ARTHUR L. STEVENS, OF ROSEVILLE, CALIFORNIA.

INDICATOR.

1,216,876.

Specification of Letters Patent. Patented Feb. 20, 1917.

Application filed April 17, 1916. Serial No. 91,711.

To all whom it may concern:

Be it known that I, ARTHUR L. STEVENS, a citizen of the United States, residing at Roseville, in the county of Placer and State 5 of California, have invented certain new and useful Improvements in Indicators, of which the following is a specification.

This invention relates to a device for attachment to freight cars and is designed to 10 indicate the weight of said cars and the date when said weight was taken, and has for its primary object to provide a simple, easily operated and permanent means for indicating weight and date which may be changed 15 by the proper person as occasion demands, and with great quickness.

Another object is to provide a means which when once applied lessens the amount of time, work and delay in indicating the 20 weight of a car and the day of its weighing, and permits the departure of the car immediately after setting the device for weight and date, while at the present time when these indications are placed upon a 25 car by stenciling, more or less time is required before the car can proceed. Time is required for the paint to dry, and further time is consumed because of the number of channels through which the orders for placing the weight on the car must pass before the work can be done and after completion. The 30 device is closed and secured against unlawful tampering by any ordinary car seal which must be broken before any change 35 can be made in the weight or date indicated, and by reason of the fact that the securing means is a universally used car seal, said cars may be reweighed and the new weight indicated at once at any place on the route 40 of the car where such new weight is desired.

With these objects in view and others to be described more fully in detail, the invention consists in the construction and arrangement of parts hereinafter set forth 45 and illustrated in the accompanying drawing, in which:

Figure 1 is a side elevation of the car weight indicator as it appears when in position on a car.

Fig. 2 is a vertical longitudinal sectional view of the same.

Fig. 3 is an end view of the indicator as seen from the left hand side, and

Fig. 4 is a vertical cross-sectional view on 55 the line 4-4 of Fig. 1.

Referring to the drawings by numerals, 10 indicates a thin casing of such length and height as is most desirable for the purpose, and comprises a front plate 11 and a rear plate 12, these plates being connected 60 together in parallel relation by end strips 13, rivets 14 passing through the two plates and the strips to secure the latter in position.

Pivoted to the top of the plate at one end on a stud 15 is a cover 16 that has downwardly projecting side flanges 17 which overlie the front and rear plates 11 and 12. A bottom 18 is pivoted on a stud 19 at the same end of the casing as the top 16 and has 70 upstanding flanges 20 to overlap the front and rear plates in a similar manner as the top 16. The end of the top 16 opposite the pivoted end is provided with a downwardly extending finger 21 that lies close against the end of the casing 10 and at about the center of the casing is a loop 22 formed on the tongue. A similar tongue 23 projects upwardly from the bottom 18 and has a loop 24 substantially in line with the loop 22, 75 these loops corresponding in position with a slot 26 in the lug 25. Through this slot and the loops 22, 24 is passed a wire 27 of an ordinary car seal 28 by means of which the cover 16 and the bottom 18 are securely 80 locked over the open top and bottom of the casing.

Within the casing 10 are two horizontal rows of indicating disks or wheels mounted 85 on pivots that extend crosswise of the casing and are riveted on their ends in the front plate 11 and the rear plate 12. These disks or wheels in the upper row are indicated by the numerals 29, 30 and 31 while those of the lower row are numbered 32, 33 and 34. Number wheels 29, 30 and 31 rotate freely, unless locked, upon horizontal pivots 35 while the lower number wheels 32, 33 and 34 are similarly mounted on pivots 36. Number wheels 29, 30 and 31 indicate the weight of the car while the wheels 32, 33 and 34 give the date when weighed. The space between the plates 11 and 12 is equal to the thickness of two disks and therefore to enable as large disks or wheels to be used as possible in the smallest casing, these disks or wheels are made to overlap as shown in Fig. 2. As there seen, the disks 29 and 31 have their indicating faces in contact with the front plate 11, while the intermediate 95 100 105 110

wheel or disk 30 is under the two previously mentioned. In the lower row disks or wheels, this position is reversed, the middle wheel 33 of the three lower wheels bearing 5 on the front plate 11, while the other two are in rear thereof and of the respective wheels 29 and 31. By this arrangement, disks or wheels of relatively large diameter can be placed in compact form and yet permitted 10 to rotate freely when they are to be set to indicate any desired number. The number wheels 29, 30 and 31 are each divided by peripheral notches 37 into ten equal parts and a number placed below each notch, the numbers extending consecutively from zero to nine, there being one number 15 for each notch. The numbers are so positioned on the wheels that the number immediately over the pivot 35 of each wheel will be displayed through a side opening 38 on the top of the front plate 11. These numbers indicate the weight of the car in hundred-weights and to make this perfectly clear, two ciphers are placed at the right of 20 the opening 38 through which the numbers on the wheel 31 are seen. Extending downwardly from the top 16 above each disk 29, 30 and 31 is a locking lug 39, said lugs engaging 25 the uppermost notches in the disks when the cover is closed and holds said disks against rotation.

Similar locking lugs 40 project upward from the bottom 18 and engage notches 41 in the peripheries of the number wheels 32, 35 33 and 34. The number wheel 32 has twelve notches in its periphery and on its face numerals 1 to 12 opposite each notch, these numbers indicating the months of a year. Wheels 33 and 34 however have ten notches 40 only in their peripheries similar to the wheels in the row above. The numbers on the face of wheels 32, 33 and 34 run in reverse order to those on the wheels above them, because the wheels of the lower row 45 are set from the underside, while those of the upper row are set from above. The wheels 33 and 34 are the year-wheels and indicate the last two numbers of the year for which they are years set. The numbers on 50 these wheels are visible through openings 42 in the front plate 11, the lowermost number on each wheel immediately beneath the pivot 36, being visible through said openings. The bottom 18 has a number of holes 55 43 formed through the bottom thereof for the escape of water and dirt from the interior of the casing.

When a freight car equipped with this device has been weighed, the top 16 is raised 60 and the several wheels 29, 30 and 31 turned by a finger to indicate the weight in 100-weights, and afterward the bottom 18 is lowered and the number wheels of the lower row are in turn set to indicate the month 65 and the year when the car was weighed.

The top and bottom are then closed so that the lugs 39 will engage notches 37 of the upper row of wheels and the lugs 40 enter the notches 41 of the lower row of wheels, thereby locking all of said wheels against 70 rotation. Afterward, a seal of the usual type employed by railroads is passed through the loops 22 and 24 of the respective tongues 21 and 23 on the top and bottom and also through the lug 25 on the front plate of 75 the casing. By this means, the wheels cannot be changed for the purpose of altering the numbers or date except by breaking the seal, in which case, the bottom 18 will drop and thereby indicate that the device had 80 been tampered with.

By the employment of the above-described device, the expense for numbering is very much reduced as there is no continuing expense after once applying the device and the 85 same may be applied for the cost of one stencil. The amount of clerical work necessary to renumber or re-stencil a car is enormously reduced and the work of changing the numbers placed in the hands of that 90 department of the railway service where it belongs. No time is lost in waiting for the paint to dry as is necessary in the present method, nor is time lost in the stenciler hunting for the car to be renumbered as the 95 change is made in the number, while the car is on the weighing scales and may be removed from the scales and at once sent upon the road. If desired, the weight indicated on the car may be changed at any time to 100 show the weight of a loaded car. Another advantage in the use of this device in the saving of time is the fact that in stormy weather it is not necessary to hold over cars for re-weighing until they dry, which is 105 necessary where the number is painted on the sides of the car, because it is well-known that paint will not adhere to the side of the car when the latter is wet.

I claim:

1. In an indicating device, the combination with a thin casing, having opposite narrow sides hinged thereto at one end, and securing means at the other end, a row of sight 115 openings being formed in one broad face of said casing near each of said hinged sides, of two rows of number wheels rotatably mounted in said casing, and means on said hinged sides to lock when closed said number wheels against rotation.

2. In an indicator, the combination with a casing having a top and bottom hinged thereto, of two rows of number wheels rotatably mounted therein, each wheel having a notched periphery and a circular row of 125 numbers on its face, and means on said top and bottom to engage when closed a notch on each wheel and prevent rotation thereto.

3. In an indicator, the combination with a casing having a top and bottom hinged 130

- thereto, a row of eight openings in one side near the top and a similar row of openings near the bottom, of two rows of number wheels rotatably mounted in said casing, 5 each wheel having a notched periphery and a circular row of numbers on its face, a number on each wheel being visible through said openings, and means on said top and bottom to engage when closed a notch in each wheel 10 to prevent rotation thereof.
4. In an indicator, the combination with a casing having a top and bottom hinged thereto at one end and having means on their other ends to hold them closed by means of 15 a seal, of two rows of number wheels rotatably mounted in said casing, each wheel having a notched periphery and a circular row of numbers on its face, and means on said top and bottom to engage when closed 20 a notch on each wheel to prevent rotation thereof.
5. In an indicator, the combination with a casing, having a top and bottom hinged thereto at one end, a finger on the opposite 25 ends of said top and bottom, said fingers adapted to overlap and provided with means for connecting the same to hold the top and bottom closed, of two rows of number wheels rotatably mounted in said casing, each wheel 30 having a notched periphery and a circular row of numbers on its face, and independently rotatable when the top and bottom are open, and a plurality of lugs on said top and bottom to engage when closed a notch
- in each of said wheels to prevent rotation 35 thereof.
6. In an indicator, the combination with a casing formed of two parallel side plates, spaced a short distance apart by end strips, a top hinged at one end to said casing and 40 having a finger at right angles thereto depending from its other end, a bottom similarly hinged to the casing and having an upstanding finger at right angles to the bottom, each of said fingers having means 45 coöperating with each other and with an opening in one of said plates by which said top and bottom may be secured in closed position by a seal, and a plurality of freely rotatable number wheels within said casing 50 adapted to be locked against rotation by the top and bottom when the latter are closed.
7. In an indicator, the combination with a casing having a top and bottom hinged thereto, and means for locking the same in 55 closed position, of two rows of number wheels freely rotatable within said casing, each wheel having a notched periphery, and a plurality of lugs projecting from both the top and the bottom to engage notches on said 60 wheels and lock them against rotation when the top and bottom are closed.

In testimony whereof I affix my signature in presence of two witnesses.

ARTHUR L. STEVENS.
